UNITED STATES PATENT OFFICE.

FRANK PIERACCINI, JR., OF SPRINGFIELD, MASSACHUSETTS, ASSIGNOR TO THE FISK RUBBER COMPANY, OF CHICOPEE FALLS, MASSACHUSETTS, A CORPORATION OF MASSACHUSETTS.

CORD FABRIC.

Application filed September 19, 1919. Serial No. 324,903.

To all whom it may concern:

Be it known that I, FRANK PIERACCINI, Jr., a citizen of the United States of America, residing at Springfield, in the county of 5 Hampden and State of Massachusetts, have invented certain new and useful Improvements in Cord Fabrics, of which the following is a specification.

My invention relates to rubberized fabrics and in particular to what are known as 10 cord fabrics which are in use in the manufacture of automobile casings.

It has for its object a fabric in which the 15 thread or positioning elements will not interfere with the action of the cords or strain-resisting elements. It has for a further object a fabric which will present a substantially flat surface with the cords parallel and without the frequent irregularities due 20 to the weft threads which are present in the usual similar fabrics. It has for a further object a fabric in which there is a firmer bond between the rubber and fabric components than is the case with similar fabrics 25 known at the present time.

My invention will now be described with reference to the accompanying drawings, in which—

Fig. 1 is a fragmentary view of a fabric 30 made according to my invention; and

Fig. 2 is a similar view of a thread fabric made according the previous practice.

What is known as "thread fabric" is a 35 type of cord fabric composed of a warp of cords, which serve as strain-resisting elements, and a weft of light thread, which preferably does not carry any strain but serves merely to hold the warp cords in position and prevent their tangling during 40 the covering of the fabric with rubber. In this usual construction the weft threads are spaced two or three to the inch, and run at right angles to the warp cords. The weft threads add nothing to the strength of the 45 fabric, and in fact prevent, in the usual construction, the proper functioning of the warp cords for the reason that they distort the cords slightly out of their normal flat position. Further, when the fabric is being 50 built into a tire casing the weft threads through their binding action frequently prevent the cords taking up the position they would naturally assume. As one of

the greatest problems in tire manufacture is the equal tensioning of all the fibrous elements these causes of distortion, however slight they may seem in themselves, become serious in their combined effect. A cord even slightly distorted from its natural path will not bear its share of the load, and will 60 accordingly cause the overburdening of other cords.

According to my invention I build the warp cords as before, and form the weft of light threads running diagonally of the 65 fabric preferably in a zig-zag course. As a single weft thread engages several cords at different longitudinal points of the fabric the retaining action of one thread is distributed over a very considerable distance, 70 thus enabling the number of weft threads to be very greatly reduced. In practice the spacing of the weft threads may be varied as desired, but I have found that two threads to the yard will give very satisfactory results. I do not wish to limit myself 75 to this spacing, however, as it will be apparent that the spirit of my invention will be retained if the spacing is great enough so that substantial distance occur between interruptions to the normal flat path of the 80 cords; or, expressed in another way, if the distance between successive weft threads is comparable with the width of the fabric (at least after this has been severed into bias 85 strips according to the usual practice) instead of being comparable, as in the old form, with the spacing of the cords. By having a wide spacing of the weft threads several advantages follow. There being 90 fewer threads there is less waviness in the cords due to the weave. The space between the threads is sufficiently great to present a relatively large intermediate surface in which the cords lie flat and without waves. 95 Due to the same cause the cords will be free to adjust themselves to their normal conditions of path and tension when they are finally built upon the core.

In coating this fabric with rubber it is 100 preferably fed through a calendar in the same manner as ordinary fabric. The diagonal filling of threads holds the cords in position so that they will not tangle nor lap over one another, while the tension exerted 105 on the cords keeps them straight. The fab-

ric may be frictioned and skim coated on one or both sides, as desired.

In Fig. 1 of the drawings 10 represents the cords or strain resisting elements, and 5 11 the diagonal filling of threads. In Fig. 2, 12 represents the weft threads laid according to the old practice. The fabric is usually cut into bias strips along lines 13 in the customary manner.

10 In the claims I have used the term "cord" to denote the strain resisting elements, of whatever material composed and of whatever construction and size; and the term "thread" to denote the filling, whether this 15 be made of what is commercially known as thread or of rubber, or other material.

I claim—

1. A fabric composed of a warp of closely spaced cords and a weft of relatively 20 widely spaced threads arranged in a zig-zag course.

2. A fabric composed of a warp of closely spaced cords and a weft of relatively

widely spaced threads arranged in a zig-zag course, the whole being coated with rubber. 25

3. A fabric composed of a warp of relatively closely spaced cords and a weft of threads diagonally disposed and spaced apart a distance comparable with the width of the fabric.

30 4. A fabric intended for use in the manufacture of pneumatic tire casings, said fabric being composed of a warp of fibrous elements capable of resisting the strain to which the completed tire structure is to be subjected, such elements being spaced relatively closely together, a weft of positioning threads arranged in a succession of obliquely disposed courses, each course being in the opposite direction from that immediately preceding it, and a layer of vulcanizable material lying on the face of the fabric and penetrating between the adjacent fibrous elements forming the warp.

40 FRANK PIERACCINI, JR.
